(57) **CLAIM**

The ornamental design for an air to water intercooler for automotive applications, as shown and described.

DESCRIPTION

FIG. 1 is a front view of an air to water intercooler for automotive applications showing our new design;

FIG. 2 is a back view thereof;

FIG. 3 is a top view thereof;

FIG. 4 is an enlarged view of the area identified as “4” in FIG. 3;

FIG. 5 is an enlarged view of the area identified as “5” in FIG. 3;

FIG. 6 is a bottom view of the air to water intercooler for automotive applications;

FIG. 7 is a left view thereof;

FIG. 8 is right view thereof;

FIG. 9 is a perspective view thereof; and,

FIG. 10 is another perspective view thereof.

The broken lines in the drawing figures show portions of the air to water intercooler for automotive applications which form no part of the claimed design.

The shade lines in the figures show contour and not surface ornamentation.

1 Claim, 10 Drawing Sheets
